(No Model.)

J. T. OBENCHAIN.

CHOP GRADER.

No. 308,977.

Patented Dec. 9, 1884.

UNITED STATES PATENT OFFICE.

JOHN T. OBENCHAIN, OF LOGANSPORT, INDIANA.

CHOP-GRADER.

SPECIFICATION forming part of Letters Patent No. 308,977, dated December 9, 1884.

Application filed May 19, 1884. (No model.)

To all whom it may concern:

Be it known that I, JOHN T. OBENCHAIN, of Logansport, Cass county, Indiana, have invented certain new and useful Improvements 55 in Chop-Graders, of which the following is a specification.

This invention relates to machines for grading chop, scalping grain, and such like milling operations.

10 The invention will be readily understood from the following description, taken in connection with the accompanying drawings, in which—

Figure 1 is a vertical section of a machine, 15 illustrating my improvement; Fig. 2, a side elevation of a portion of the casing of the same, and Fig. 3 a horizontal section of the same. Figs. 2 and 3 are upon a somewhat larger scale than Fig. 1.

20 The machine is in the form of a cylinder standing upright and designed to elevate the material operated upon.

In the drawings, A represents the upper head of the machine; B, the lower head; C, 25 the outside cylindrical casing, formed of vertical staves, the alternate ones of which are to be secured rigidly by screws or otherwise to the top and the bottom heads; D, buttons attached to the rigid staves of the casing and 30 serving to secure in place the intermediate staves, which are to be so fitted as to be removable; E, an open-top cup within the casing near its bottom; F, a space between the bottom of the cup and the lower head of the 35 casing; G, feet at the base of the cup by which the cup is secured rigidly to the lower head of the casing; H, a cup-like rim depending, within the casing, from the upper head of the casing; I, a cylindrical sieve-jacket of wire-cloth or other bolting material, disposed concentrically within the casing and extending 40 from the rim of one cup to the rim of the other, being united to both; J, vertical strengthening-ribs upon the outside of the sieve-jacket;

45 K, rings at the bottom, center, and top of the jacket, secured to the vertical strips and serving to bind the parts of the sieve structure; L, an inlet-spout, by which material is fed to the interior of the sieve-jacket at its bottom, 50 the spout connecting with the bottom cup; M, a vertical shaft axially disposed in the ma-

chine and journaled in bearings secured to the two heads of the casing; N, four beater-boards secured to the shaft extending the entire length of the space within the jacket and 55 arranged in the form of a long four-sided box open at the corners; O, inclined conveyer-flights secured to the outer faces of the beater-boards; P, a longitudinal blast-crack formed by one of the open corners of the box-like 60 beater; Q, right and left hand screws disposed through and across the shaft in which they are journaled, and taking into nuts secured to the beater-boards; R, the driving-pulley of the machine; S, a sweeping-arm secured to 65 the shaft and arranged to sweep the upper surface of the lower head of the casing; T, the outlet-spout for such of the material as has passed through the sieve-jacket; U, an air-inlet through the top head of the casing into 70 the interior of the box-like beater; V, gussets of rubber or cloth or other flexible material covering three of the four corner-cracks of the beater; W, an annular space between the sieve-jacket and the casing, and X the space within 75 the sieve-jacket.

The alternate staves of the casing, being rigidly secured to the top and bottom heads, serve as rigid frame parts for the machine, and thus permit me to dispense with the usual extra 80 frame. The intermediate staves may be removed at will, thus rendering the interior of the machine readily accessible.

The sieve-jacket is formed in two longitudinal halves, and the rings K are divided diametrically, whereby the entire structure of the sieve-jacket is formed in two substantial pieces. The end rings of the jacket structure are rabbeted in order that when the two parts of the jacket structure are put in place these 90 rabbets will engage neatly with the rims of the top and bottom cups. The two parts of the jacket structure are to be held into position by joint bolts, by buttons, or by any other suitable means.

95 The conveyer-flights are so inclined as to convey material upward when the beater is in motion. They are preferably formed of sheet metal inserted into saw-cuts in the outer faces of the beater-boards, and their peripheral contour should correspond substantially to a circle.

The bolts Q are provided with collars at each side of the main shaft in order to prevent end play of the bolts. There are lock-nuts outside the beater-boards, and also square, so that 5 they may be turned. There are two sets of these screws, one set near each end of the beater-boards. The screws of one set pass through the shaft at different levels, so as not to interfere with each other. The office of these screws 10 is to adjust the transverse dimension of the beater-box, which may be done by turning the screws from the outside of the beater in an obvious manner.

The gussets V should be flexible enough to 15 permit the ready expansion and contraction of the beater-box when adjusted by the screws. One of the corner-cracks is left open to form a blast-crack, and it is desirable, though not essential, that even this blast crack should be 20 provided with gussets at the ends of the crack, so as to limit the length of the blast-crack to the length of the sieve-surface of the jacket.

The closer a rotary conveyer, or beaters acting in conjunction with it, fits its surrounding jacket the more rapid will be the forward motion of the material—that is, there will be 25 less negative slipping of the material. I utilize this law in the regulation of my conveyer action. To increase the rate of feed through 30 the machine I enlarge the beater and bring its peripheral elements closer to its surrounding jacket. To reduce the rate of feed I contract the size of the beater.

The material to be graded enters the machine 35 through the spout L, and thereby reaches the interior of the sieve-jacket. The beater elevates it and forces the finer matter through the sieve-jacket. The finer matter falls down the outside of the sieve-jacket through the 40 space W into the space F, where it is swept to the discharge-spout T. The coarser matter, refusing to pass through the sieve-jacket at any time during its upward travel, is discharged through the spout U, which spout 45 should be arranged tangentially with reference to the sieve-jacket.

The rotation of the beater would naturally produce a blast outward through to the sieve-jacket, in case the air had admittance to the 50 space X between the outside of the beater and the inside of the sieve-jacket; but my experience has shown me that this blast is very feeble in its effect, as it finds an outlet through the entire area of the sieve-cloth. The sieve-cloth 55 is really subjected to the action of compressed air, rather than to the action of an air-blast in current. The consequence is that flour lodges upon the outside of the sieve-cloth and

gradually reduces its efficiency, the weak outflow of the air through all of the interstices 60 of the cloth at once not being sufficient to dislodge the flour. In my device I admit the air to the inside of the beater and revolve the column of air with the beater. Centrifugal force tends to throw this air outward, but it can only 65 escape through the single open outlet or blast-crack P. The effect of this arrangement is to subject the sieve-jacket to the action of a sharp, thin, vertical, and forcible blast of air concentrated upon a very limited area of the 70 sieve-jacket. This traversing forcible blast effects the entire jacket during the rotation of the beater.

The beater may have more or less than four sides, and internal fan-blades may be added, 75 if found desirable, to increase the effect of the blast.

In the construction set forth the beater-box forms the air-pressure-producing element of the machine; but it is obvious that the air 80 may be compressed elsewhere and conveyed to the interior of the beater, which may then serve as a wind-box provided with a longitudinal blast-crack.

I claim as my invention—

1. In a chop-grader, the combination of the alternate fixed staves of the casing, the intermediate removable staves joining the edges thereof, the lower head having the alternate staves rigidly secured thereto, and the upper 90 head rigidly secured to the alternate staves, constructed as set forth, whereby the alternate staves form the sole support for the top head, and the usual frame-work exterior to the casing is dispensed with.

2. In a chop-grader, the combination of a cylindrical jacket, a rotary conveyer within said jacket, several longitudinal series of inclined flights attached to said conveyer, and means, substantially as set forth, for adjusting 100 the exterior diameter of the conveyer, and thereby regulating the rate of conveyance without altering the inclination of the flights or the speed of the machine.

3. In a chop-grader, the combination of a 105 vertical circular sieve-jacket, a flat-sided hollow beater-box with a single longitudinal blast-crack at one of its peripheral corners, and several longitudinal series of inclined conveyer-flights secured to the beater-box.

JOHN T. OBENCHAIN.
